UNITED STATES PATENT OFFICE.

ALBERT H. LEVENE, OF PHILADELPHIA, PENNSYLVANIA.

CORE OR OTHER RACK.

1,385,012.

Specification of Letters Patent. Patented July 19, 1921.

Application filed December 11, 1919. Serial No. 344,235.

To all whom it may concern:

Be it known that I, ALBERT H. LEVENE, a citizen of the United States, residing in the city and county of Philadelphia, State 5 of Pennsylvania, have invented a new and useful Core or other Rack, of which the following is a specification.

My present invention comprehends a novel construction of a core rack for carrying plates with sand cores or molds into ovens. It is so arranged that the bars forming the shelves of the rack are readily removable by simply elevating them. This permits the quick changing of the spacing 10 between the shelves to allow for larger cores or molds. The removable shelf bars are interlocked in such a manner that they cannot move laterally or longitudinally for such movement would shake and spoil the sand 15 cores.

The rack is constructed preferably of structural metal in such a manner that a very rigid construction is provided.

The rack of my present invention can be 25 employed as a rack *per se* which is adapted to be transported by means of an elevating truck or the corner posts may have secured to them rollers or antifriction devices, in order to facilitate its movement from one 30 place to another.

My invention further comprehends novel means for adjustably securing the cross beams to their support and a novel construction and arrangement of interlocking 35 structural beams or bars which interlock in such a manner that any lateral or longitudinal relative movement of the parts is prevented and the position of these structural beams may be readily adjusted in accordance 40 with the character of material which is to be carried by the rack.

Other novel features of construction and advantage will hereinafter more clearly appear in the detailed description.

For the purpose of illustrating my invention, I have shown in the accompanying drawings preferred embodiments of it which in practice will give satisfactory and reliable results. It is, however, to be understood that these embodiments are typical 50 only and that the various instrumentalities of which my invention consists can be variously arranged and organized and that the invention is not limited to the precise arrangement and organization of these instrumentalities as herein set forth.

Figure 1 represents, in front elevation, a rack, embodying my invention.

Figs. 2 and 3 represent, in perspective, interlocking structural metal beams which are 60 employed.

Fig. 4 represents, in side elevation, a rack, embodying my invention.

Fig. 5 represents a section on a section line paralleling line 8—8 of Fig. 6. 65

Fig. 6 represents a section on line 6—6 of Fig. 1.

Fig. 7 represents a section on line 7—7 of Fig. 1.

Fig. 8 represents a section on line 8—8 70 of Fig. 6 but showing a channel instead of a T-bar.

Fig. 9 represents, in perspective, one of the structural metal bars constructed to receive a channel. 75

Fig. 10 represents, in perspective, a channel bar adapted to coöperate with the T-bar seen in Fig. 9.

Fig. 11 represents, in perspective, another embodiment of my invention in which a different form of channel bar is employed. 80

Fig. 12 represents, in end elevation, the construction seen in Fig. 11.

Fig. 13 represents, in section, the manner in which the parts are interlocked when two 85 channel bars are employed.

Fig. 14 represents, in perspective, the construction seen in Fig. 13 as the parts appear as they are being brought into locking position. 90

Fig. 15 represents, in perspective, an angle which may be employed in place of the T-bar seen in Fig. 2.

Similar numerals of reference indicate 95 corresponding parts.

Referring to the drawings.

1 designates the corner posts which consist of structural metal bars and as illustrated are in the form of angles having a flange provided with a longitudinal row of 100 vertically spaced apertures 2. 3 designates lower cross bars consisting of angles as shown which are bolted or otherwise secured to the corner posts 1. In order to reinforce said bars gusset plates 4 are employed which are fixed to the bars 3 and also to the lower structural metal bars 5 which latter as shown are in the form of angles which are adjustably connected to the corner post 1 by means of fastening devices 6, except the intermediate cross bar 5, see Fig. 7, which is secured to the bars 3 by means of gusset plates 11.

7 and any desired type of fastening devices such as bolts or rivets 8.

The upwardly extending flange 9 of a bar 5 is provided with a series of spaced recesses 10, the contour of which varies in accordance with the type of structural bar which it is to receive and I prefer to illustrate it as adapted to receive the T-bars 11, see Figs. 1 and 3 which are provided with the slots 12 opening through the bottom face of the web of the T-bar so that the bottom wall of the slot 12 will rest on the wall 13 of a recess 10 while the flanges forming the head of the T-bar will rest on the walls 14 of the recess 10. 15 On the inner face of the angles 5 an angle 15 is secured which is provided with an aperture 16 which registers with an aperture 17 in the web of the T-bar 11 so that a fastening device 18 such as for example a bolt and 20 nut can be employed to rigidly connect the bars 11 with the angles 5. The corner posts 1 have fixedly secured to them near their upper end the bars 19 by means of gusset plates 20 and fastening devices 21. Fixed 25 to the bars 19 are the cross bars 22 which as illustrated in Fig. 1 are in the form of angles having connected to them the structural bars 23 in a similar manner to that already described in connection with the bars 30 11 and the angles 5.

The corner posts 1 have adjustably connected with them by means of fastening devices 24 a series of superimposed structural bars 25 which as best seen in Figs. 1 and 2 35 are illustrated as consisting of T-bars having spaced recesses 26 therein corresponding in contour to the type of structural cross bar 27 which they are to receive and for purposes of illustration, I have shown the structural cross bars 27 as consisting of a T bar except that the uppermost T-bar 25 is provided with a series of double slots 28 to receive the channel bars 29, see Figs. 1, 9 and 10. The channel bars 29, see Fig. 10, are provided 40 with the slots 30 and the wall 31 between the slots 28, see Fig. 9, is preferably slightly lower than the upper face of the upwardly extending flange of the T-bar.

Instead of employing the structural bars 50 25 of a T-shaped contour, I may employ a channel bar of any desired contour. In Figs. 11 and 12, I have shown a U-shaped channel bar 32 the flange 33 of which is higher than the flange 34 and the web of 55 the T-bar 27 is provided with a series of slots 35 which permit the flange 33 of the U-bar to be engaged by the head of the T-bar while the slots 36 have their bottom wall resting on the flange 34 of the U-bar.

60 In Fig. 14, I have shown interlocking bars as consisting of two channels each flange of which is provided with slots 37 and 38 arranged in pairs in a channel bar 39 which can be used in lieu of the bars 25 while the 65 upper channel bars 40 which can be used

in lieu of the bars 27 are provided with slots 41 and 42 arranged in pairs.

It will be understood from the foregoing that in all the embodiments of my invention as herein shown, the adjustable bars such as 27 which form the shelves of the rack can be readily removed whenever desired or placed in position and when in position they interlock with the rack bars 25 in such a manner that any relative lateral or longitudinal movement between such parts is prevented.

The side walls of the slots 12 in case a T-bar is employed, as seen in Fig. 3, extend on both sides of the flange of the structural bars 25 so that any relative longitudinal movement of the bars 11 with respect to the bars 25 is prevented. The head of the T-bars 11 or 27 which are seated preferably substantially flush in the slots 10 or 26, respectively, prevent any lateral or relative movement of such bars. When it is desired to change the position of a bar 27 or 29 all that it is necessary to do is to elevate it and move it into register with the desired slots 90 and then lower it to adjusted position or any of such bars can be entirely removed if desired.

It will be understood from Figs. 11 and 12 that when the interlocking rack bars are in 95 the form of a T-bar and U-bar as shown, any relative or lateral movement of such rack bars when interlocked is positively prevented and the same holds true in the case of the bars seen in Fig. 14 and also in the 100 case of the channel bars and T-bars in Fig. 8.

It will be apparent that the interlocking structural metal or other bars such as 25 and 27, 22 and 23, 32 and 27, or 25 and 29 form the shelves of the rack and can be 105 readily adjusted without the use of tools to vary the size or shape of the shelves, in order to adapt them to the character of the material which is to be supported on the rack and while the rack is especially adapted to be used as a cross rack, it will be apparent that it can be used for any desired purpose.

It will now be apparent that I have devised a new and useful core or other rack 115 which embodies the features of advantage enumerated as desirable in the statement of the invention or the above description, and while I have, in the present instance, shown and described preferred embodiments there- 120 of which will be found in practice to give satisfactory and reliable results, it is to be understood that the same are susceptible of modification in various particulars without departing from the spirit or scope of the invention or sacrificing any of its advantages.

Having thus described my invention, what I claim as new and desire to secure by Letters Patent, is:—

1. In a rack, corner standards, laterally 130

extending structural metal bars supported by said standards and having upwardly directed flanges provided with T-shaped recesses opening through the tops of the flanges, and T-bars disposed at an angle to said bars and seated in the recesses of said flanges, said T-bars having their webs recessed to fit over said flanges, whereby relative movement of said T-bars with respect to 10 said flanged bars except in an upward direction is prevented.

2. In a rack, corner standards, laterally extending structural metal bars supported by said standards and having upwardly directed flanges provided with recesses open- 15

ing through the tops of the flanges and structural metal bars disposed at an angle to said first bars and adapted to seat in said recesses, said recesses in said flanges conforming to the contour in cross section of 20 said second bars, said second bars having recessed portions which fit over said flanges, whereby any movement except in an upward direction of said second bars with respect to said first bars is prevented.

ALBERT H. LEVENE.
